UNITED STATES PATENT OFFICE.

EDWARD E. JOHNSON, OF PAINESVILLE, OHIO.

DESIGN FOR AN ORNAMENTAL BORDER FOR CARPETS, &c.

SPECIFICATION forming part of Design No. 17,293, dated May 3, 1887.

Application filed March 28, 1887. Serial No. 232,819. Term of patent 7 years.

To all whom it may concern:

Be it known that I, EDWARD E. JOHNSON, a citizen of the United States, and a resident of Painesville, in the county of Lake and State 5 of Ohio, have invented a certain new and useful Design for Borders; and I do hereby declare that the following is a full, clear, and exact description of the invention, which will enable others skilled in the art to which it applies to make and use the same, reference being had to the accompanying drawings, which form a part of this specification, and in which—

Figure 1 is a view of one form of my new design for border as seen upon a metallic binding for carpets and floor or oil cloths. Figs. 15 2 and 3 are views of other forms of the same.

Similar numerals of reference indicate corresponding parts in all the figures.

My design has relation to borders, and more 20 particularly to such as are adapted to be used upon metallic bindings for carpets, oil-cloths, floor-cloths, and similar articles; and it consists in the new ornamental design for the same, as hereinafter more fully described and 25 claimed.

In the accompanying drawings, the numeral 1 indicates the binding-strip, which is formed with two (more or less) broken longitudinal beaded lines, 2, upon its face, and with one longitudinal uninterrupted beaded line, 3, near the inner edge parallel with the broken beaded lines, which are parallel with each other and with the edges of the strip. One or more broken beaded lines may be made upon the 30 face of the strip, Fig. 2 of the drawings show-

ing three beaded lines with one unbroken beaded line near the inner edge. The broken beaded lines are preferably made with their joints or spaces lapping, but the spaces between the broken beaded lines may, if desired, be made registering, as shown in Fig. 3. 40

Having thus described my design, I claim and desire to secure by Letters Patent of the United States—

1. The design for an ornamental border for binding for carpets, oil-cloths, and similar articles, consisting of two parallel broken beaded lines having their joints or spaces lapping, and an unbroken beaded line parallel to the broken lines near the inner edge of the strip, 45 as shown and set forth.

2. In a design for an ornamental border for binding for carpets, oil-cloths, and similar articles, consisting of two parallel broken beaded lines and an unbroken beaded line parallel to the broken lines and near the inner edge of the strip, as shown and set forth. 55

3. In a design for an ornamental border for binding for carpets, oil-cloths, and similar articles, consisting of parallel broken beaded lines and an unbroken beaded line parallel to the broken beaded lines and near the inner edge of the strip, as shown and set forth. 60

In testimony that I claim the foregoing as my own I have hereunto affixed my signature 65 in presence of two witnesses.

EDWARD E. JOHNSON.
